UNITED STATES PATENT OFFICE.

EDWARD DAVIES, OF BROOKLYN, NEW YORK, ASSIGNOR TO THE ANSONIA CLOCK COMPANY, OF ANSONIA, CONNECTICUT.

CLOCK.

SPECIFICATION forming part of Letters Patent No. 231,769, dated August 31, 1880.
Application filed July 20, 1880. (No model.)

To all whom it may concern:

Be it known that I, EDWARD DAVIES, of Brooklyn, in the county of Kings and State of New York, have invented certain new and 5 useful Improvements in Clocks, of which the following is a specification.

My invention relates to clocks with what are known as exposed escapements—that is to say, clocks in which the escapement-work is 10 contained within a recess or depression in the center of the face of the dial, which is closed at the back by a center plate to conceal the rest of the movement. In such clocks the center plate is usually fastened to a false plate 15 secured to posts projecting from the front plate of the movement, and has fixed in it the posts for supporting the escapement-bridge.

The object of my invention is to so support the center plate of the dial that the posts supporting the escapement-bridge may be fixed in the front main plate of the movement, and thus simplify the construction of such clocks, and also to so support the said plate that it will 20 readily accommodate itself to dials in which 25 the collars or flanges surrounding their center openings are of various depths; also, to enable various kinds of dial center plates to be used with one movement.

To these ends my invention consists in the 30 combination, in a clock-movement, of a dial having a central opening, two posts projecting forward from and fixed in the frame of the movement, an escapement-bridge secured to said posts within the opening of the dial, a 35 loose-dial center plate fitting upon said posts, and means preferably consisting of a spring or springs for holding the dial center plate tightly against the opening in the dial.

The springs employed may be of spiral or 40 other form, and if spiral, may be coiled upon the posts which support the escapement-bridge.

In the accompanying drawings, Figure 1 represents a central section through a portion 45 of a clock-movement and a dial embodying my invention. Fig. 2 represents a similar section in a plane at right angles to Fig. 1, and Fig. 3 represents a front or face view of the dial.

Similar letters of reference designate corresponding parts in all the figures.

It will be understood that in illustrating my invention I have only represented such parts of a clock-movement as are necessary to show its operation, all superfluous parts being omitted.

A and B designate, respectively, the front and back main plates of the movement composing, with posts connecting them, the frame of the movement. C designates an open center dial supported by arms *a*, projecting from 55 and secured to the front plate, A. D designates the center arbor or main staff of the movement carrying the hands. All these parts are similar in construction and arrangement to corresponding parts in clock-movements as 60 commonly constructed, and a more extended description thereof is unnecessary.

E designates two posts secured in and projecting from the front main plate, A, of the movement, and having secured to their outer 65 ends an escapement-bridge, F, supporting the usual escapement-work G, which is arranged in the opening in the center of the dial of an exposed escapement-clock.

H designates the center plate of the dial, 70 which closes the opening in the dial in rear of the escapement-work G, thus concealing the rest of the wheel-work of the clock from view.

As most clearly represented in Fig. 1, the center dial-plate fits loosely upon the two posts 75 E, it being adapted to move or slide upon them longitudinally of the posts, and in order to keep the loose plate up close against the flange *b*, surrounding the central opening in the dial and forming the side of the cavity in 80 which the escapement-work is arranged, I insert a spring or springs between the front main plate of the movement and the loose center plate which exert a constant forward pressure upon the said center plate.

The springs I are here shown as of spiral 85 form coiled around the posts E E, and this form of spring is preferably employed. As the posts are made of uniform diameter, the springs and center plate may be both placed 90 upon the posts before securing the escapement-bridge F thereto.

The means for supporting the center plate is very simple, being in all respects similar to that used to support a simple escapement- 95 100

bridge, except in the addition of the springs. It will be observed that if the flanges *b* upon the dials are not of uniform depth, or the arms *a*, supporting the dials, are not of exactly uniform length, the inequalities will be automatically compensated for by the yielding center plate, which will adjust itself to close the opening in the center of the dial.

Instead of springs, any other means might be employed to hold the center plate against the dial—as, for instance, nuts engaging with screw-threads on the posts or collars on the posts.

What I claim as my invention, and desire to secure by Letters Patent, is—

1. The combination, in a clock-movement,

of a dial having a central opening, two posts fixed in and projecting forward from the frame of the movement, an escapement-bridge secured to said posts within the opening of the dial, a loose dial center plate fitting upon said posts, and means for holding said plate against the dial, substantially as specified.

2. The combination of the frame, the open center dial, C, the posts E, the escapement-bridge F, the escapement G, the loose dial center plate H, and the springs I, substantially as specified.

E. DAVIES.
